(57) **CLAIM**

The ornamental design for an display screen for graphical user interface, as shown and described.

DESCRIPTION

FIG. 1 is a perspective view of a display screen with graphical user interface showing the new design;

FIG. 2 is a front view thereof, the graphical user interface shown separate and enlarged for ease of illustration;

FIG. 3 is a perspective view of a display screen with graphical user interface, according to a second embodiment;

FIG. 4 is a front view of the second embodiment, the graphical user interface shown separate and enlarged for ease of illustration;

FIG. 5 is a perspective view of a display screen with graphical user interface, according to a third embodiment; and,

FIG. 6 is a front view of the third embodiment, the graphical user interface shown separate and enlarged for ease of illustration.

The broken line showings of the display screen in FIGS. 1, 3, and 5 are for the purpose of illustrating environmental structure and form no part of the claimed design.
